By his Attorneys,

Inventor
Joseph H. Pierce

C. A. Howat & Co.

UNITED STATES PATENT OFFICE.

JOSEPH H. PIERCE, OF GLENWOOD SPRINGS, COLORADO.

HINGE.

SPECIFICATION forming part of Letters Patent No. 364,290, dated June 7, 1887.

Application filed November 12, 1886. Serial No. 218,735. (Model.)

To all whom it may concern:

Be it known that I, JOSEPH H. PIERCE, a citizen of the United States, residing at Glenwood Springs, in the county of Garfield and 5 State of Colorado, have invented certain new and useful Improvements in Hinges; and I do hereby declare the following to be such a full, clear, and exact description of the same as will enable others skilled in the art to which it applies 10 to make and use the same, reference being had to the accompanying drawings, and to the letters and figures of reference marked thereon.

My invention relates to improvements in 15 door-hinges, and aims to provide a hinge of such construction that the door may be opened in either direction and may be set at any desired angle across the threshold without changing the hinges.

20 The invention consists in certain novel features hereinafter described and claimed.

In the accompanying drawings, which fully illustrate my invention, Figures 1 and 2 are side elevations taken from opposite sides; and 25 Fig. 3 is a horizontal sectional view of a door provided with my improved hinge, the several positions of the door being indicated by dotted lines in Fig. 3. Fig. 4 is a detail perspective view of the hinge.

30 Referring to the drawings by letter, A designates the door, and B the door-frame.

C designates the hinge, which is composed of two leaves or sections, D E, similar in size and construction to the ordinary hinge in common use.

35 F is a leaf or section of a length equal to the thickness of the wall or door-jamb, and G is an arm or leaf which extends from the outer edge of the leaf or section F to the central line 40 of the door, at which point they are pivotally connected thereto. The several leaves or sections of the hinge are flexibly connected by means of pintle-pins H, inserted through loops or eyes formed on their contiguous edges.

45 The section D is secured to the door-frame in the usual manner by screws or similar devices, and is provided in its upper edge with a notch, d, the purpose of which will presently appear. The section E is provided in its upper edge with a similar notch, e, which is formed

at such a point that when the two sections are brought together the notches d e will coincide. The outer end of the section G is provided at its upper and lower corners with the vertical extensions g, which serve as journals for the 55 hinge.

I I are bearing-plates, which are secured rigidly to the side of the door on its central line. These plates I are arranged above and below the end of the section G, and have the 60 perforated arms i, which extend outward therefrom at right angles and are formed integral therewith. The journals g of the section G engage the perforations of these extensions i, and thereby pivotally connect the hinge to the 65 door. That edge of the door which, when the door is closed, is adjacent to the door-jamb to which the section D of the hinge is secured is provided with recesses J to receive the section E of the hinge. These recesses are faced 70 with metal, so as to reduce the wear thereon and give a neat finish to the door.

K designates a catch which is secured to the door on the side opposite to that to which the end section of the hinge is secured and at the 75 upper end of the recess J. This catch consists of a plate, K, secured to the door, and a hook, K', projecting from the edge of the plate at its upper end. This hook K' engages the notch e in the upper edge of the section E and enters 80 the notch d in the edge of the section D, thus holding the door to the hinge and at the same time allowing the edge of the door to come in close contact with the jamb.

Where so desired the catches K can be dispensed with and hooks formed on the edge of the metal facings of the recesses J, which will engage the edge of the sections F; and the pintle-pins of the hinges may, if desired, be extended so as to serve for both hinges, and 90 thereby secure the simultaneous action of the same.

L are lifting knobs or handles, which are provided near each edge of the door at any convenient height.

In operation, when it is desired to operate the hinge in the same manner as the hinges now in common use, the catches K are allowed to engage the upper edges of the hinge-sections, as before described, when the door will 100

be held to the hinge and allowed to swing in one direction only. If the door be lifted slightly, so as to disengage the catches from the hinge-sections, the door will be permitted to turn on the journals of the section G, which, together with the flexible connections of the hinge-sections, enables the door to swing in either direction and to assume every conceivable position, as will be readily understood upon reference to the dotted lines in Fig. 3.

Having thus described my invention, what I claim, and desire to secure by Letters Patent, is—

The combination, with the door and the door-

jamb, of the hinge comprising a series of flexibly-connected sections, one end section being fixedly secured to the door-jamb and the other one pivotally secured to the door on the central line of the same, and the catches secured to the side of the door and projecting beyond the edge thereof to engage the edge of one of the intermediate hinge-sections, substantially as specified.

JOSEPH H. PIERCE.
